CLAIM

The ornamental design for a hull of a sailing craft, as shown and described.

DESCRIPTION

FIG. 1 is a top plan view of a hull of a sailing craft showing my new design;

FIG. 2 is a bottom plan view thereof;

FIG. 3 is a side elevation thereof, the opposite side being a mirror image of that shown; and

FIG. 4 is a front elevation view thereof.

FIG. 1.

FIG. 2.

FIG. 3.

FIG. 4.
